Atty.

UNITED STATES PATENT OFFICE.

NORMAN P. HARSHBERGER, OF CHICAGO, ILLINOIS.

SHINGLE.

Application filed December 4, 1922. Serial No. 604,733.

This invention relates to shingles for covering roofs, and has for its object the production of suitable shingles for the purpose so formed that the exposed part thereof may be locked down by the adjacent shingles so as to prevent the exposed part from being turned up by the wind or by warping or in any other manner. Another object of the invention is to provide shingles of such shape that the appearance of the roof, after having been covered by the shingles, will be pleasing to the eye. A further object is to provide shingles of this nature of such shape that they can be easily laid and will form a very effective waterproof cover for the roof. Other objects of the invention will be apparent from consideration of the accompanying drawings and the following description thereof.

Of the drawings, Fig. 1 is a plan view of a plurality of shingles properly assembled on the roof; Fig. 2 is a plan view of a single shingle overlapping normally another shingle; and Fig. 3 is a sectional view along the line 3—3 of Fig. 2.

So far as my invention is concerned the substances of which my shingles are composed is immaterial, but I prefer for the purpose substances which may be formed into sheets or long strips, and then may be conveniently cut by means of dies or otherwise into individual units, which are then to be applied to the roof in general in a manner somewhat similar to the ordinary manner of applying shingles. When shingles are made in this manner, when applied to the roof, as they are ordinarily more or less pliable, the exposed portions of the shingles are sometimes bent upwardly by the wind or are otherwise bent out of shape, the consequence is that the appearance of the roof is objectionable and the protection offered by the roof is more or less diminished. In order to prevent this deformation I provide means for locking down the exposed parts of the shingles to the adjacent shingles.

In general the shingles which I provide are square or at least rectangular shaped and comprise a main or body portion 5, which is normally covered by the adjacent shingles, the exposed portion 6 and the locking portion 7; the locking portion being fixed in any suitable manner to the cover part of the portion of the shingle which will

be exposed when laid. This locking member 55 may be fixed to the shingle in any suitable manner, but I prefer for the purpose cutting slits 8 in the exposed portion of the shingle whereby a portion 7 is free to be bent upwardly or downwardly. The ends of this 60 portion form tongues or lugs which may be slipped under the edges of the adjacent shingles. When the shingles are laid the lower row of shingles 9 are laid and fastened in any ordinary manner by nails 10. The next 65 row of shingles 11 are then laid staggered with reference to the shingles 9 with the tongues 12 projecting under the edges 13 of the two adjacent underlying shingles. The layer 14 is then laid alternating with 70 the shingles 11 but in line with the shingles 9 and with the tongues of the shingles 14 locked under the edges 15 of the adjacent underlying shingles; and so on until the 75 roof is covered, each shingle as thus laid being fastened by nails 10 near the side corners thereof.

Referring to Fig. 1 it will be seen that the exposed portion of each of the shingles forms a square or rectangular shaped figure which 80 is pleasing to the eye, and, by cutting off the lower corners of the shingles, the exposed edges 16, together with the edges 17 of the horizontal slit 8 gives a pleasing appearance to the roof, so that the appearance of the 85 roof as a whole is very pleasing to the eye. It should be understood that my invention is not to be considered as confined to square or rectangular shaped shingles, as the shingles may be diamond shaped or other shapes 90 in general without departing from the spirit of my invention as disclosed by the following claims.

In order to facilitate the laying of the shingles and to prevent any tearing tendency 95 of the edges of the slotted portion of the shingle I provide in the shingles slits 17 which not only allow the tongues to be bent inwardly more readily but allow the edges 13 to pass more freely over the tongue without danger of tearing the shingle. Although the exact shape of the tongues is not material to the broad principle involved, yet I prefer to have the outer edge of each tongue parallel with the adjacent side of 100 the shingle, as is indicated in the drawings. In this way this edge of the tongue projects at right angles under the adjacent shingle

edge and thus the maximum amount of tongue surface for the tongue area is projected under the adjacent shingle.

I claim as my invention:

5. 1. An article of manufacture comprising a shingle, a tongue fixed to the inner portion of said shingle at a material distance from the edges, said tongue having oppositely disposed projections thereon, said projections being adapted to lie under the respective edges of two adjacent underlying shingles; said shingle having a plurality of slits partly surrounding said tongue whereby said tongue may be bent downwardly out 15 of the plane of the shingle.
10. 2. An article of manufacture comprising a shingle having interior slits therein spaced a material distance from the edges of the shingle, said slits being continuous and enclosing an oblong-shaped portion, the portion of the shingle within said slits being adapted to be bent out of the plane of the shingle and said portion having oppositely disposed projections thereon adapted to lie 25 under two adjacent underlying shingles.
15. 3. A plurality of shingles adapted to cover a roof and a tongue integral with and fixed to each of said shingles a material distance from its lower edge, said tongue being bent downwardly out of the plane of 30 said shingle and being adapted to project under the edges of two adjacent underlying shingles.
20. 4. An article of manufacture comprising a shingle, an elongated tongue integral with the inner portion of said shingle, said tongue having oppositely disposed projections thereon, said projections being adapted to lie under the respective edges of the 40 two adjacent underlying shingles.
25. 5. An article of manufacture comprising a rectangularly-shaped shingle having an elongated tongue fixed to one corner of said shingle, two of the edges of said tongue 45 being substantially parallel with the respective adjacent edges of said shingle, and adapted to lie under the respective cor-

responding edges of two adjacent underlying shingles.

6. A plurality of shingles covering a roof, 50 each of said shingles having a tongue integral with and fixed thereto a material distance from its lower edges, each of said tongues having oppositely disposed integral projections, and the respective projections 55 extending beneath the two adjacent underlying shingles.

7. A shingle having locking means adjacent one corner, said means comprising an integral tongue, said shingle having an 60 opening through the shingle and registering in shape and position with said tongue, two edges of said tongue adjacent said corner being parallel with the respective converging adjacent outer edges of the shingle. 65

8. A rectangularly-shaped shingle having two slits therethrough, adjacent one corner spaced apart and respectively parallel with the adjacent edges of the shingle, and having other slits therethrough connecting the ends of said slits which are most remote from said corner.

9. A roofing shingle having its body provided with a slit arranged wholly within the border edge of the body and forming 75 a tongue adapted to interlock with the edge of another shingle.

10. A roofing comprising a plurality of shingles adapted to be arranged obliquely in rows and each shingle of one row overlapping a shingle in another row and having a tongue formed wholly within the border edge thereof and engaging underneath the edge of the other shingle. 80

11. A roof comprising a plurality of shingles, one edge of each shingle passing over an inner portion of an adjacent overlying shingle, all of said inner portions being spaced a material distance from the edges of said shingle. 85

In testimony whereof, I hereunto set my hand.

NORMAN P. HARSHBERGER.
